UNITED STATES PATENT OFFICE.

FRED MILTON MEREDITH, OF TORONTO, ONTARIO, CANADA.

SETTING-UP DEVICE FOR STICKER OR MOLDING MACHINES.

1,316,494.

Specification of Letters Patent. Patented Sept. 16, 1919.

Application filed September 30, 1918. Serial No. 256,231.

To all whom it may concern:

Be it known that I, FRED MILTON MEREDITH, a subject of the King of Great Britain, of the city of Toronto, county of 5 York, Province of Ontario, Canada, have invented certain new and useful Improvements in Setting-Up Devices for Sticker or Molding Machines, of which the following is a specification.

10 My invention relates to improvements in setting-up devices for sticker or molding machines, and the principal object of my invention is to provide for accuracy and speed in setting up the knives in the class of machines mentioned, thereby producing a better quality of work and increasing output. Another object of the invention is to make my device adjustable to fit all makes of molding machines, whether of inside or outside types. A still further object of my invention is to utilize certain fixed planes as starting points or foundations, so to speak, from which all measurements are made in setting up the knives or blades. A still further object of the invention is to make use of my device so that templets may be held thereby to permit permanent records to be made of the configuration of the cutting edge of the knives so as to facilitate the work in again setting up these knives to reproduce the same patterns. Further objects of the invention will appear in the following specification.

A device of the class described within my invention comprises a portable supporting member; a plurality of adjustable supports carried thereby, and holding or clamping means carried by said adjustable supports designed to carry the setting-up gage according to the location of use thereof and whereby the setting up of the knives carried by the vertical and longitudinal cutter-heads can be accurately and quickly effected.

45 Figure 1 is a perspective view of a setting-up device within my invention. Fig. 2 is a plan view of one end of my setting-up device positioned for use against the fence of a sticker or molding machine, portion of 50 which fence and portion of the bed of the machine being shown. This view also shows a knife undergoing adjustment. Fig. 3 is a vertical cross section on the line 3—3, Fig. 1, on an enlarged scale. Fig. 4 is a vertical section on the line 4—4, Fig. 3. Fig. 5 is a longitudinal section, on an en-

larged scale on the line 5—5, Fig. 1. Fig. 6 is a vertical cross section on the line 6—6, Fig. 1. Fig. 7 is a perspective view of the rear side of one of the clamps for the gage-plate. Fig. 8 is a longitudinal section, on an enlarged scale, on the line 8—8, Fig. 7. Fig. 9 is a longitudinal section, on an enlarged scale, on the line 9—9, Fig. 7. Fig. 10 is an end view of the clamp for the gage-plate positioned underneath the rail, showing the support therefor. Fig. 10^a is a face view of one end of the gage-plate supported by one end of the clamp which is positioned underneath the rail, and Fig. 11 is a plan view of a templet upon which has been traced the cutting points of the knives for record purposes.

In the drawings, like characters of reference refer to the same parts.

75 It is well-known in the art that the lips of the cutter-heads of a machine, after use, are very seldom of a uniform distance from the axes of rotation thereof, and they, therefore, cannot be relied upon as starting points from which to accurately set up the knives in combination with the well-known scale-gage. Now in putting my invention into practice, I support the scale-gage independently of the cutter-heads, and, therefore it 80 is immaterial in setting up knives by means of my device, whether the lips of the cutter-heads be a uniform distance from the axes of rotation thereof or not, and the result is that a comparatively unskilled operator can set up his knives very readily and with absolute accuracy, whereas according to the old practice, much time was consumed in setting up the knives, and this work could only be successfully done by 85 highly skilled and careful workmen. It, therefore, follows that by reason of my invention, comparatively unskilled operators can do as good work in a shorter space of time, and even with less waste of material 90 than can possibly be accomplished by skilled operators in the old way.

To set up the knives on one or more cutter-heads, the supporting member, base, or rail, of the device is positioned on the bed 105 of the sticker or molding machine, in a manner similar to that of the pressure-shoe and against the fence, after certain supporting members hereinafter referred to have been removed therefrom. When the supporting member, base, or rail, has been positioned, the same is clamped in place by the

ordinary pressure-feet, and then the supporting members mentioned are replaced. The knives carried by the cutter heads are then adjusted to do the required work, after 5 which the said supporting members are removed, and the supporting member is then removed from the machine.

It is to be understood that by means of my invention, the scale-gage can be supported at any angle so that the cutters or 10 knives carried by the vertical cutter-heads may be accurately positioned, as desired.

A device within my invention comprises a suitable supporting member, base or rail A, 15 which carries suitable supporting members hereinafter particularly referred to. The supporting member which supports the scale-gage when adjusting the knives carried by the upper horizontal cutter-head, may be 20 conveniently constructed as follows: B is a post provided with a foot C. This foot is clamped to the rail A to be adjustable longitudinally thereof, and to be readily removed therefrom. For this purpose, the 25 preferred construction comprises a rail D, (supported by a block *w* which is carried by the rail A), having a guiding-rib E extending longitudinally thereof. The underside of the foot C is slotted to fit the rib E so 30 that this foot may move longitudinally on the rail A. The clamping-screw F operates through a slot G formed in the foot C so as to allow for the adjustment of this foot and its post and the securing of the same in 35 adjusted position, since this screw screws into the rail D. A bracket H is vertically adjustably mounted on the post B in any suitable manner. The preferred construction comprises a key I mounted in the bore 40 J of the bracket and operating partly in the key-way L formed in the post B and in a correspondingly shaped key-way, formed in the bracket H. This is a construction well-known, and the bracket H is keyed 45 from rotary movement on the post. M is a pressure-screw held in the bracket H and pinching against the key I, so as to hold the bracket H in adjusted position. Pivoted 50 between the lugs N of the bracket M by means of the pin O, is an arm P, which, in the position of the parts illustrated in Fig. 1, rests against the portion Q of the bracket H. Pivoted to the outer end of the arm P is a clamp R, conveniently constructed as 55 follows: S is a plate, to one side of which is suitably secured a pair of plates T, spaced apart, between which is pivoted, by the pin U, the free end of the arm P. Formed in one of the plates T is a segmental slot 2, 60 through which passes a clamping screw 3, carried by the arm P. The construction just described permits the clamp R to be moved into various positions and held in the required position. 4 is a plate overlapping 65 one end of the plate S, and at the opposite

end of this plate is a correspondingly-shaped plate 5. These plates are provided with a pair of flanges 6, as shown clearly in Figs. 1 and 9, so that the scale-gage, which is in the form of a plate 7, may be held in said 70 clamp. Since this scale-gage is to be removed from the said clamp and mounted in the other clamps with which my device is provided, some means must be provided for permitting the ready withdrawal of the plate 75 7 from said clamp. To conveniently permit of this, I provide the plate 4 with an ear 8 in which is fixed one end of a rod 9 which operates through a plate 10 suitably secured at the other end to the plate S, and 80 is secured in the plate 11, carried by the plate S, and held in spaced relationship in respect of the plate 10 so as to permit of the movement of the plate 11. For this purpose, the said plate is slotted as shown at 85 12, Fig. 8, through which slot extends the screw 13 carried by the plate S. The head of this screw overlaps the sides of the slot 12. Mounted on the rod 9, and between the plates 10 and 11 is a coiled-spring *a'*, which 90 functionates to keep the plate 4 against its associated end of the plate S, when the plate 7 is not carried by the clamp R. When this plate 7 is mounted in the clamp R, the plate 4 is of course held against one end 95 of the plate 7 to retain it in place. By gripping the plates 10 and 11 in the hand, the plates 11 and rod 9 will be moved to shift the position of the flanged plate 4.

The clamp R, just described, is that used 100 to support the scale-gage or plate 7 when the operator is setting up the knives carried by the upper horizontal cutter-head. An identical clamp R' is carried by the far 105 end of the rail A, and this clamp is for the purpose of supporting the scale-gage or plate 7 (see Fig. 10) when setting up the knives carried by the lower horizontal cutter-head. The arm P' is offset as shown in Fig. 10, and is supported by a slotted plate 110 C' co-operating with a rail D' supported on the block *w'* which is carried by the rail A. The clamping-screw F' holds the plate C' in adjusted position.

Now in order to set up the blades or knives 115 carried by either or both of the vertical cutter-heads, I provide a supporting member positioned intermediate the clamps already described, and carried by the rail A. This supporting member is constructed very similar to the supporting member for the clamp R, and comprises a post 14 carried by a foot 15, which co-acts with the rail 16, carried by the supporting member A, after the manner 120 well understood. The clamping screw 17 125 holds the foot 15 in adjusted position. The bracket 18 supports the pin 19 which pivots the arm 20 to said bracket. This bracket is mounted to turn horizontally on the post 14 by means of the head 21 chambered as shown 130

at 22 (see Fig. 6) to receive the upper end of the post 14. The foot 23 of the bracket is in alinement with the head 21 and the post 14 passed therethrough. The said foot 5 is provided with a pair of lugs 24, spaced apart, through which passes the clamping screw 25 so that this foot may be pinched around the post 14 to hold the said bracket in adjusted position. An open slot 26 is 10 formed in the upper side of the foot 23 to receive the arm 20. This construction permits of the ready manipulation of this arm, and it will be understood that since the bracket 18 can be turned on the post 14, the 15 clamp 27 carried by the arm 20, can be positioned to support the scale-gage or plate 7, for the setting up of the knives carried by both of the vertical cutter-heads. The said clamp 27 comprises an upper bracket composed of horizontal and vertical plates 28 and 29. By reason of the screw or equivalent element 30, the plate 29 is pivoted to the supporting member 31, longitudinally adjustably mounted on the arm 20. Through 25 the segmental slot 32 formed in the plate 29 extends the clamping screw 33. The construction just described permits of the adjustment of the upper bracket of the clamp 27 so that the scale-gage or plate 7, carried 30 by the lower bracket of this clamp, can be adjusted into any angular position around the screw 30, and held in this position during the setting up of the knives or blades carried by the vertical cutter-heads. The lower 35 bracket of the clamp 27 comprises horizontal and vertical plates 34 and 35. By means of the screw or equivalent element 36, the said lower bracket is pivoted to the said upper bracket, through the medium of the plates 40 28 and 34. The horizontal plate 28 is provided with a segmental slot 37, through which operates the clamping screw 38 held in the plate 34 so that the lower bracket of the clamp 27 may have an adjustment independently 45 of the upper bracket. Operating against the back of the plate 35, is a plate 39 provided with a slot 40, through which extends the stud 41, carried by the plate 35. Formed from the plate 39 is an ear 42 in 50 which is held a rod or pin 43 which has sliding movement through the stud 41. A coiled-spring 44 is mounted on the pin 43 between the stud 41 and ear 42 so that the scale-gage or plate 7 may be removably 55 clamped between the flanges *a* and *b* of the plates 39 and 35.

To prevent other than longitudinal movement of the supporting member 31 on the arm 20, suitable means is employed. The 60 preferred means comprises a key-way *c* formed longitudinally in the arm 20 and a correspondingly shaped key-way *d* formed in the member 31, and held in these key-ways is a key *e*, against which operates a clamp-screw *f* carried by the member 31.

I shall now describe the manner in which my device is employed. Two planes or starting points, positioned at right angles to each other, are essentially considered in making use of my invention. In setting up the cutters carried by the horizontal cutter-heads, the inner face *g* of the fence *h* (Fig. 2) 70 must be used as a reference plane, and in setting up blades or knives on the vertical cutter-heads, the surface of the bed *i* of the machine is similarly used. As before described, to position the rail *A*, the clamps *R* and 27, and the supporting members therefor, will be removed from the rail, and after the rail *A* has been positioned against the 80 inner face *g* of the rail *h*, and upon the top surface of the bed *i*, it is clamped in position by the usual pressure feet, one only of which is indicated by the dotted line *j* in Fig. 2. Then the supporting member for the clamp 85 *R* is placed in position and adjusted in respect of the upper horizontal cutter-head, the axis of rotation of which is indicated by the broken line *k* in Fig. 2. The clamp *R* is then thrown down into the position illustrated in Figs. 1 and 2, and the scale-gage or plate 7 placed therein. This scale-gage or plate is provided with the usual scales whereby the depth and width of cut may be measured, and since it is well-known, it requires no particular description. On my scale-gage or plate, I provide at the right-hand end thereof, two parallel lines *l* and *m* and either of these lines must be in alinement with the inner face *g* of the rail *h* 90 when setting up knives or blades carried by the upper horizontal cutter-head. The outer line *l*, I have termed the fence line, and the inner line *m*, I have termed the finished working line. When I am setting up blades 100 or knives on the upper horizontal cutter-head when the vertical right hand side cutter is to be used, the fence line *l* must be in alinement with the face *g*. When I am setting up the knives just mentioned, and not using 105 the vertical right-hand side cutter, the clamp *R* is adjusted so that when the scale-gage or plate 7 is placed therein, the finished working line *m*, will be in alinement with the face *g* of the fence *h*. To secure this 110 adjustment, I use the following preferred means: Formed in the flanged plate 5 is a pair of longitudinal slots *n* through which pass the screws *o*. The distance separating the left-hand end of the slots *n* from the 115 shank *p* of the screws *o*, is equal to the distance separating the lines *l* and *m*, and, therefore, when the plate 5 is moved to move the left-hand end of the slots *n* into contact with the shanks *p*, the screws *o* are tightened 120 up, the finished working line *m* will be absolutely in alinement with the face *g* when the scale-gage or plate 7 is placed in the clamp *R*.

We will consider that we are going to set 130

- up the knife or blade *r* shown in Fig. 2. Naturally the same will be placed against the cutter-head (not shown), and then the cutting-edge of the knife will be positioned 5 upon the horizontal line of the scale-gage or plate 7, required to obtain the desired depth of cut, and the said knife or blade will also be adjusted in respect of the width of the work. The adjustments once secured, the 10 knife is clamped in place after the usual manner and the clamp *R* is thrown up around its pin *O* to permit the cutter-head, not shown, to be turned in order to adjust the other knives.
- 15 The clamp *R'* receives the scale-gage or plate 7 to adjust the knives or blades carried by the lower horizontal cutter-head, and the use thereof will be understood by one skilled in this art after what has been already set 20 forth. It will be understood that in mounting the scale-gage or plate 7 in the clamp *R'*, the operator will use the scale backward, as shown in Fig. 10, starting his longitudinal measurements from the end vertical line indicated.

In Fig. 3, I show the scale-gage or plate 7 mounted in the clamp 27 so as to provide for the setting up of the cutters or blades carried by the vertical cutter-heads. The dotted line *s* represents the axis of rotation of 30 one of the vertical cutter-heads, and the figure *t*, represents in dotted lines one of the knives or cutters. In adjusting these knives or cutters, the fence-line *l* is placed in alinement with the face of the bed *i*, where the lower horizontal cutter-head is in use. Should the lower horizontal cutter-head be 35 not in use, the finished working line *m* must be placed in alinement with the face of the said bed *i*. Without further elaboration, it 40 will be understood just how these cutters or knives are adjusted in vertical position, as before described. By loosening the clamping screw 33, the clamp 27 can be moved 45 around the screw or pin 30 to support the scale-gage or plate 7 at the desired angle so as to secure the corresponding adjustment for the cutters or knives carried by the vertical cutter-heads. In making such angular 50 adjustment, one of the lines *l* and *m* must be placed in alinement with the face of the bed *i* according to which one will be used.

The bracket 18 is raised or lowered to allow for vertical adjustment of the scale-gage or plate 7, by any suitable means, such as the following, when adjusting either of the lines *l* and *m* in respect of the surface 55 of the bed *i*; *u* is an adjusting screw threaded through the upper end of the head 21, and resting against the upper end of the post 14. When the required adjustment has 60 been made, the nut *v* will be used to lock the screw *u* in adjusted position.

Positioned at each end of the preferred 65 form of rail are the two blocks *w* and *w'*

whereby the bottom of the rail in the vicinity of the vertical cutter-heads will be supported above the surface *i* of the bed of the machine so as to allow for the free passage of cutters thereunder in case of necessity. One of the blocks *w* is adjustably carried by one end of the rail *A* by any suitable means; the preferred construction comprises a clamping screw *x* passing through the longitudinal slot *y* and screwing into a nut *z* 70 carried by the block. A rib *a'*, carried by the block supporting the nut *z*, extends into the slot *y* so as to insure movement of this block longitudinally of the supporting member *A*. This adjusting feature just described, as well as the capability of adjustment of the supporting members for the clamps *R* and 27, is for the purpose of enabling my device to be used on machines of 80 different makes.

In Fig. 11, I show a templet 60 upon which has been traced the configuration of the cutting edge of the knives set up to cut a given shape. This templet can be properly preserved so that for any future duplication of the design recorded thereon, all that is necessary will be for the operator to place the templet in the desired clamp and fit the cutting edges of the knives to the configuration of the shape carried thereby, thus greatly saving in time and insuring 90 accuracy of adjustment.

While I have described what I consider to be the best embodiment of my invention, I desire it to be understood that the disclosure herein is merely illustrative, and I do not wish to be confined to the construction herein shown and described except in so far as that may be made necessary by reason of the prior art and the terms of my 100 claims.

Claims.

1. A device of the class described comprising a portable base designed to be placed upon the bed of a sticker or molding machine and against the inner face of the fence thereof; a plurality of adjustable supporting means carried by said base, and a gage-plate mounted in any of said adjustable supporting means, as may be desired, according 110 to the location of the cutter-heads in respect of which the knives are to be set up; certain markings on said gage-plate being positioned in alinement with the upper surface of said bed and the inner face of said 115 fence, as may be desired, for the purpose specified.

2. A device of the class described comprising a portable base; a pair of members positioned one at each end of said base and 120 each designed to support in horizontal position a suitable gage-plate; adjustable clamping means for said members carried by said base; a supporting member positioned intermediate said pair of members 125

- and designed to support a gage-plate in vertical position, and adjustable clamping means for said intermediate supporting member carried by said base.
- 5 3. A device of the class described comprising a portable base; a pair of members positioned one at each end of said base and each designed to support in horizontal position a suitable gage-plate; adjustable clamping means for said members carried by said base; a supporting member positioned intermediate said pair of members and designed to support a gage-plate in vertical position; adjustable clamping means 10 for said intermediate supporting member carried by said base, said intermediate supporting member comprising parts relatively adjustable to support the gage-plate in any convenient angular position with respect to 15 the base.
4. A device of the class described comprising a portable base; a vertically-disposed post adjustably carried by said base; a horizontally-disposed supporting member 20 carried by said post and designed to support a gage-plate in horizontal position so that a certain line of the scale thereof will be in alinement with that side of said base which is placed against the fence of a sticker, and 25 means connecting said horizontally-disposed supporting member with said vertically-disposed post so as to permit said horizontally-disposed supporting member to have independent vertical and circular movement on 30 said post.
5. A device of the class described comprising a portable base; a vertically-disposed post adjustably carried by said base; an adjustable horizontally-disposed supporting member carried by said post and 35 designed to support a gage-plate in a horizontal position so that a certain line of the scale thereof will be in alinement with that side of said base which is placed against the fence of a sticker, and means connecting 40 said horizontally-disposed supporting member with said vertically-disposed post so as to permit said horizontally-disposed supporting member to have independent vertical 45 and circular movement on said post.
6. A device of the class described comprising a portable base; a post positioned at one end of said base; means whereby said post is adjustably and removably positioned 50 on said base; a bracket carried by said post, and held against rotary movement on said post; means whereby the bracket may be clamped in adjusted position on said post; an arm pivoted at one end to one side of 55 said bracket; a horizontally-disposed plate pivoted to the free end of said arm; means whereby the said plate may be held in adjusted position on said arm, and clamping means associated with said plate so as to 60 permit a gage-plate to be held thereby when 65 placed thereagainst so as to insure that a certain line of the scale carried by said gage-plate will be in alinement with that side of said base which is placed against the fence of a sticker, for the purpose specified. 70
7. A device of the class described, comprising a portable base; a post positioned intermediate the ends of said base; means whereby said post is adjustably and removably positioned on said base; a bracket carried by said post; means whereby said bracket is clamped to said post; an arm pivoted at one end to said bracket, and overhanging said base, and a supporting member carried by said arm and designed to support a gage-plate after the manner set forth and for the purpose specified. 75
8. A device of the class described comprising a portable base; a post positioned intermediate the ends of said base; means whereby said post is adjustably and removably positioned on said base; a bracket carried by said post; means whereby said bracket may be vertically adjusted on said post; an arm pivoted at one end to said 80 bracket, and overhanging said base, and a supporting member carried by said arm and designed to support a gage-plate after the manner set forth and for the purpose specified. 85
9. A device of the class described comprising a portable base; a post positioned intermediate the ends of said base; means whereby said post is adjustably and removably positioned on said base; a bracket carried by said post; an arm pivoted at one end of said bracket, and overhanging said base, and a supporting member mounted on said arm to be adjustable longitudinally thereof; means for holding said supporting member 90 against axial movement when in its adjusted position; an upper bracket comprising upper and lower plates disposed substantially at right angles to each other; means whereby said upper plate is pivoted to said supporting member; means whereby said upper plate may be held in adjusted position; a lower bracket comprising upper and lower plates disposed substantially at right angles 95 to each other; means whereby the upper plate of said lower bracket is coupled to the lower plate of said upper bracket so as to have a rotary adjustment around said pivotal connection; means whereby said lower bracket is held in adjusted position, 100 and means whereby a gage-plate may be supported by the lower plate of said lower bracket after the manner set forth and for the purpose specified. 105
10. In a device of the class described, a clamp comprising a longitudinal plate; an arm; means whereby said plate is adjustably pivoted to one end of said arm; a pair of flanges carried by one end of said longitudinal plate and projecting beyond the 110
- 115
- 120
- 125
- 130

- upper side thereof; a movable plate positioned at the other end of said longitudinal plate and provided with a pair of flanges which also project beyond the said upper 5 side of said plate; a spring-provided rod located adjacent the underside of said longitudinal plate and coupled to said movable plate, and means carried by said longitudinal plate to support said spring-provided rod 10 and whereby said rod may be manually actuated to shift said movable plate away from the median line of said longitudinal plate and may be spring-actuated in the opposite direction, for the purpose specified.
- 15 11. In a device of the class described, a clamp comprising a horizontally-disposed plate; a pair of plates projecting at right angles beyond one side thereof and spaced apart, one of said plates being provided with 20 a segmental slot; an arm pivoted at one end between said plates; a clamping-screw extending through said slot and screwing into said arm so as to hold said plate in ad-
- justed position; a plate positioned against the rear side of said first-mentioned plate 25 and provided with a pair of flanges projecting beyond the face of said first-mentioned plate; a pair of screws passing through longitudinal slots formed in said flanged plate and screwed into said first-mentioned plate, 30 the construction described permitting said flanged plate to be moved longitudinally of said first-mentioned plate; a plate positioned at the opposite end of said first-mentioned plate and overlapping the rear side thereof; 35 a pair of flanges carried by said third-mentioned plate and projecting beyond the front side of said first-mentioned plate; and spring-provided means coupled to said third-mentioned plate and supported by 40 said first-mentioned plate whereby said third-mentioned plate may be moved longitudinally of said first-mentioned plate and then brought back to rest.

FRED MILTON MEREDITH.
